UNITED STATES PATENT OFFICE.

GUY S. LANE, OF PHILADELPHIA, PENNSYLVANIA.

ATTACHMENT FOR TELEPHONES.

Application filed October 10, 1922. Serial No. 593,516.

This invention relates to attachments for telephones and one of the primary objects of my invention is to provide a convenience for the user, especially useful under circumstances requiring the use of the right hand, or when the telephone must be held when in use.

Another object is to provide an attachment of the character described which can be applied to existing telephones.

The foregoing, together with such other objects as may hereinafter appear, or are incident to my invention, I obtain by means of a construction, the preferred embodiments of which I have illustrated in the accompanying drawing, wherein:

Fig. 1 is an elevation of the usual form of telephone stand, transmitter and receiver, in connection with which my invention is most useful; and Fig. 2 is a cross sectional view illustrating details of my improvements.

Referring now to Fig. 1, the reference numeral 7 indicates the stand having the usual base 8 and provided at the top with the transmission mechanism 9 and the receiver hook 10, the receiver being indicated at 11.

As is well understood, the hook 10 operates a switch located within the stand 7 for making and breaking connection with particular exchange, the weight of the receiver 11 being sufficient to hold the switch in open position as long as the receiver is carried by the hook.

The hook 10, as is also customary, has eyes 12 in its forks.

I attach a knob A to the eye of that fork of the receiver hook which in service is nearest the user. This knob is provided with an annular lip or flange 13 of greater diameter than that of the opening in the eye and has a reduced end portion 14 adapted to fit neatly within such opening. The central portion of the base of the knob is recessed as at 15 to receive the shank 16 of an attaching button a, the head of the

attaching button having a diameter greater than the opening of the eye 12. The button and knob are clamped about the eye by means of the screw 17, which securely holds the parts in place.

The device is used as follows: The receiver is taken off the hook and grasped between the thumb and first finger in the usual manner and the small finger of the left hand is crooked around the knob A and the telephone is held suspended. With the receiver placed to the ear and the knob grasped in this manner the transmitter is automatically brought adjacent the mouth in position for use. The weight of the stand causes the hook to remain in circuit-closing position (for the reason that the point of support is to one side of the pivot point of the hook and, therefore, to one side of the center of gravity).

The device is very useful where the telephone is located in such manner that the stand must be lifted when the telephone is in use and it, of course, releases the other hand for any purpose that may be necessary. The device can be applied to any standard telephone.

What I claim is:

1. The combination with a telephone having a stand and a forked telephone receiver hook, of telephone suspension means comprising a member secured to said hook adapted to be grasped by the receiver holding hand and lying outside of the opening between the forks to permit insertion and removal of the receiver in the usual manner.

2. The combination with a telephone having a stand and a forked telephone receiver hook, of telephone suspension means comprising a knob secured to one of the forks of the hook and lying outside of the opening between the forks to permit insertion and removal of the receiver in the usual manner.

In testimony whereof I have hereunto signed my name.

GUY S. LANE.
